UNITED STATES PATENT OFFICE.

ORVILLE APPLEBY, OF SAN FRANCISCO, CALIFORNIA.

TRANSMISSION-HUB.

1,272,182.

Specification of Letters Patent. Patented July 9, 1918.

Application filed November 11, 1916. Serial No. 130,895.

To all whom it may concern:

Be it known that I, ORVILLE APPLEBY, a citizen of the United States, residing at San Francisco, in the county of San Francisco 5 and State of California, have invented new and useful Improvements in Transmission-Hubs, of which the following is a specification.

In auto-trucks, as at present constructed, 10 it is always the case, so far as my knowledge extends, that the truck is designed only for a comparatively low speed, this low speed being necessary in order to propel the auto-truck with an engine of moderate power. 15 Especially is this the case with auto-trucks which have been formed by conversion from ordinary motor cars. When converting a motor car into an auto-truck, a reduction gear is employed to increase the power at 20 the expense of speed. But it is often found as, for instance, when the load on the car is but a light one or when the car is running on a very smooth road or on a downward incline, that the car can be run at a high rate 25 of speed without the expenditure of great power. With the ordinary means for converting a car into a motor truck, advantage cannot be taken of these conditions, for the reason that there is no way of recovering 30 the increased speed at the expense of the power.

One object of the present invention is to provide mechanism whereby either the speed of a motor car can be reduced with an increase of power, so that the car can serve as 35 an auto-truck, or, if desired, the speed relation can remain unchanged, so that the converted auto-truck can be run at high speed.

A further object is to provide mechanism 40 whereby a large number of different speeds may be imparted to a motor car from the same power.

A further object of the invention is to provide a construction by which the main 45 portion of the weight of the load of the car is thrown on the axle housing, and not on the axle, as at present, thereby relieving the axle of all strain, except that sustained in driving the car.

50 In the accompanying drawing, Figure 1 is a vertical section of my improved transmission hub; Fig. 2 is a horizontal section thereof.

55 Referring to the drawing, 1 indicates a spoke of a driving wheel of a motor car, bolted, as shown at 2, to an outer drum 3

around a drum 4, said drums forming a transmission casing. The inner drum 4 is secured by bolts 5 to the flaring end of the housing 6, said housing being also supported by a circular flange 7 around a cylindrical inner portion 8 of the housing. Through said housing extends the driving axle 9 having a tapering end 10 contained within, and keyed to, a tubular sliding-gear shaft 11, the outer surface of which is angular in form, here shown as square with the corners chamfered. To the drum 3 is secured by pins 12 a ring 13, having internal gear teeth 14. Anti-friction rollers 15 are carried on rings 16 and are interposed between the outer edge of the ring 13 and the inner surface of the flange 17 of the drum 4, so that the drum 3 can rotate without friction relatively to the drum 4 supporting the axle. 75

Said drum 3 is extended to form a cylindrical cavity 18, which receives a transmission device 19 in its neutral position, said device being slidable on the sliding gear shaft 11, and comprising a large gear wheel 20 and a small gear wheel 21 secured together by screws 22, which also secure to the inner face of the gear wheel 20 a circular plate or disk 23, the object of said disk being to hold in place a pusher plate 24, to 85 which is screwed a pusher rod 25 extending through a hole in the drum 4 parallel with the driving axle, and by which said transmission device is shifted. When said transmission device is shifted inwardly, the teeth 90 of its larger gear wheel 20 engage the teeth of a number of idle pinions 26 arranged at equal intervals around the axle and meshing with pinions 27, the pinions 26 and 27 rotating on roller bearings 28 around stud 95 shafts 29 screwed in said drum 4, said pinions 27 meshing with the teeth of the internal gear ring 13 secured to the drum 3.

By this means the speed of the wheel is reduced one-half, increasing the power proportionately, since the number of revolutions per minute of the drum 3, which is attached to the wheel, is one-half that of the transmission device 19 which rotates with the sliding gear shaft 11 rotatable with the 105 axle.

It will readily be seen that this reduced speed is obtained whatever be the original speed of the axle, whether high, low or intermediate.

110 By shifting the transmission device outwardly the teeth of the smaller gear wheel

21 mesh with an internal gear wheel 31 formed in a still further reduced portion 32 of the drum 3, said gear wheels 21 and 31 thus forming, in effect, a clutch and causing 5 the drum 3, and the wheel attached thereto, to rotate at the same speed as the axle, by reason of the fact that the transmission device 19 still rotates at the same speed as the sliding gear shaft 11, and therefore as the 10 axle, whatever be its speed, whether high, low or intermediate.

By this means a reduction in speed can be obtained suitable for converting a motor car into a motor truck, since half the speed is 15 obtained and the power increased. At the same time, if desired, by merely shifting the gear, the original speed can be employed at any time when suitable.

It is desirable when making a change in speed that the shifters of the two driving wheels be shifted not simultaneously but one slightly after the other. Many mechanisms which need not be herein specified can be employed for effecting this result.

25 The present mechanism not only provides a simple and convenient means of conversion of the driving mechanism of an ordinary car into that of an auto-truck at a lower speed and also of reconversion into 30 the original speed, but it has the great advantage that the main portion of the weight of the load of the car is now carried, not by the axle, but by the axle housing, and is thereby transmitted, through the transmission mechanism and the anti-friction wheels, to the hubs and to the driving wheels without throwing any strain due to the load upon the axle. The anti-friction rollers are interposed between the drum 4 and the ring 35 17, which is rigidly secured to the drum 3, to serve the purpose of transmitting the load from one drum to the other without any friction tending to cause loss of power. In order to permit the part of the drum 3 40 adjacent to the outer end of the sliding gear shaft to rotate relatively thereto without undue friction, ball bearings 33 are interposed therebetween, and ball bearings 34 are also interposed between the reduced 45 portion of the drum 3 and the nut 35 which is screwed upon the threaded end of the axle and holds the wheel in place.

An important advantage of this invention is that the conversion can be made by simply changing the driving wheels and attaching the shift mechanism and brakes, no other change being necessary.

I claim:—

1. In a transmission hub, the combination 60 of an axle, a housing therefor, a drum axially secured to said housing, a vehicle wheel rotatable around the axle, an internal gear wheel rotatable with the vehicle wheel, a 65 rotatable therewith, means carried by the

housing for transmitting motion from the gear wheel in its inner position to the internal gear wheel but at a slower speed of rotation, devices secured to the gear wheel and wheel respectively to transmit motion 70 direct to the wheel from the gear wheel in its outer position, and means for shifting said means.

2. In a transmission hub, the combination 75 of an axle, a housing therefor, a drum axially secured to said housing, a vehicle wheel rotatable around the axle, an internal gear wheel rotatable with the vehicle wheel, a 80 rotatable therewith, an idle gear wheel carried by the housing for transmitting motion from the gear wheel in its inner position to the internal gear wheel but at a slower speed of rotation, devices secured to the gear wheel and wheel respectively to transmit motion 85 direct to the wheel from the gear wheel in its outer position, and means for shifting said means.

3. In a transmission hub, the combination 90 of an axle, a housing therefor, a drum axially secured to said housing, a vehicle wheel rotatable around the axle, an internal gear wheel rotatable with the vehicle wheel, a 95 rotatable therewith, pairs of idle gear wheels carried by the housing for transmitting motion from the gear wheel in its inner position to the internal gear wheel but at a slower speed of rotation, devices 100 secured to the gear wheel and wheel respectively to transmit motion direct to the wheel from the gear wheel in its outer position, and means for shifting said means.

4. In combination, a driving axle, a vehicle wheel driven thereby, a housing for the 105 axle, a drum secured to said housing, a drum secured to the wheel, a ring secured to said drum and having internal gear teeth, anti-friction rollers between the ring and the drum to which it is not secured, a sliding 110 gear shaft around said axle, a transmission device slidable on, but rotatable with, said sliding gear shaft, comprising a gear wheel, and a clutch member, a clutch member carried by said second-named drum with which 115 said first clutch member is adapted to be moved into engagement, means carried by said housing, and with which said gear wheel is adapted to be moved into engagement, for transmitting motion from said 120 gear wheel to said internal toothed ring, and means for shifting said transmission device.

5. In combination, a driving axle, a vehicle wheel driven thereby, a housing for the axle, a drum secured to said housing, a 125 drum secured to the wheel, a ring secured to said drum and having internal gear teeth, anti-friction rollers between the ring and the drum to which it is not secured, a sliding gear shaft around said axle, a transmission 130

device slidable on, but rotatable with, said sliding gear shaft, comprising a gear wheel and a clutch member, a clutch member carried by said second-named drum with which 5 said first clutch member is adapted to be moved into engagement, pairs of gear wheels carried by said housing, and with which said gear wheel is adapted to be moved into engagement, for transmitting motion from said 10 gear wheel to said internal toothed ring, and means for shifting said transmission device.

6. The combination of a driving axle, a driven wheel, a stationary housing for the axle, means slidable longitudinally relatively 15 to the axle for transmitting motion in one of its positions direct from the axle to the wheel, and means carried by the housing forming a medium through which said slidable means can transmit motion in another 20 of its positions indirectly from the axle to the wheel.

7. The combination of a driving axle, a

driven wheel, a stationary housing for the axle, an internal gear ring secured to the wheel, a device slidable longitudinally relatively to the axle for transmitting motion in one of its positions direct from the axle to the wheel, and means supported by the housing for transmitting motion in another of its positions indirectly to said gear ring. 25 30

8. The combination of a driving axle, a driven wheel, a stationary housing for the axle, an internal gear ring secured to the wheel, a device slidable longitudinally relatively to the axle for transmitting motion in 35 one of its positions direct from the axle to the wheel, a drum secured to the housing surrounding said internal gear ring, anti-friction rollers between said drum and gear ring, and means supported by the drum for 40 transmitting motion from the axle to the gear ring by means of said slidable means in another of its positions.

O. APPLEBY.
